UNITED STATES PATENT OFFICE.

FRANCIS I. FLOWERS, OF TARRYTOWN, NEW YORK.

IMPROVEMENT IN SIDE BARS FOR VEHICLES.

Specification forming part of Letters Patent No. **142,011**, dated August 19, 1873; application filed December 16, 1872.

To all whom it may concern:

Be it known that I, FRANCIS I. FLOWERS, of Tarrytown, in the county of Westchester and State of New York, have invented certain new and useful Improvements in Side Bars for Carriages; and do hereby declare that the following is a full, clear, and exact description thereof, reference being had to the accompanying drawing making a part of this specification, in which—

Figure 1 is a side elevation of a carriage containing my improvement. Fig. 2 is a vertical longitudinal section of said bar upon a central line. Fig. 3 is a side elevation of the wooden portion of said bar detached, and Fig. 4 is a like view of the metal portion of the same.

Letters of like name and kind refer to like parts in each of the figures.

The design of my invention is to produce a side bar which shall possess all the elasticity of steel and the toughness of wood, and shall retain its shape or "set" while in use; and to this end said invention consists, as a new article of manufacture, in a side bar, constructed substantially as and for the purpose herein-after specified.

In the annexed drawing, A represents a wooden bar, having the general form of one-half of an elliptic spring, which bar is divided longitudinally and horizontally upon a central line, and between the sections thus formed is placed a strip of whalebone, B, that corresponds in width thereto, and has a thickness equal to

about one-quarter the thickness of said wooden portion A at its ends. The wooden sections A and whalebone B are first given the desired curved form and cemented together, so as to insure the relative longitudinal positions of their contiguous surfaces, after which the bar thus formed is placed upon a steel bar, C, which corresponds thereto in width and shape, and is provided upon its ends with sockets c that receive the ends of said bar. The wood and steel parts A and C are now firmly united by means of a wire, D, which is wound spirally around the same, after which the whole is preferably covered and protected by a raw-hide casing, E.

The spring or side bar thus constructed possesses the requisites of elasticity and toughness, and will retain its form much longer than though composed wholly of wood or metal.

Having thus fully set forth the nature and merits of my invention, what I claim, is—

The spring-bar, consisting of the wooden sections A and A, central whalebone strip B, and steel bottom strip C, constructed and combined by means of the encircling spiral wire D, substantially as and for the purpose specified.

In testimony whereof I have hereunto set my hand this 13th day of December, 1872.

FRANCIS I. FLOWERS.
